UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

CAR CONSTRUCTION

Original application filed October 20, 1928, Serial No. 313,906. Divided and this application filed February 1, 1930. Serial No. 425,259.

My invention relates to the construction of railway freight cars, and more particularly to the walls, floors or doors thereof whether such parts are rigidly secured to the car 5 proper or hinged thereto, and comprises integral cast metal members forming a frame in combination with preferably cast metal panels or units which form the load retaining portions of the walls, floors or doors of 10 the car and which are rigidly and removably secured to the frame.

A further object consists of forming a preferably cast metal panel with a web formed into a bulge projecting outwardly 15 from the interior of the car so as to increase the cubical capacity of the car to haul freight which bulge merges into the panel adjacent its perimeter, and a further object is to form the central part of such a bulge 20 of thicker material than the portions thereof adjacent the margins of the panel. Such an arrangement provides great strength to support a load for the amount of material used.

Another object is to form such cast metal panels or units so that they can be readily detached and removed from the frame and the adjacent panel.

By nature of their requirements railway 30 freight train cars are out of doors substantially all of the time, therefore, are subjected to corrosive action of the elements, and while paint and other non-corrosive coatings have been applied to the car parts, 35 such protection not only has been found to be expensive in time and money, but the lading removes the coating. This is particularly true of the inside of open type cars which are turned upside down in unloading 40 machines causing the load to slide across the inside surface of the car body and also when the discharging load slides across the surface of a drop door and also when the long lading rests upon the lowered drop end gate 45 of a gondola car the friction therebetween caused by the movement of the car also removes the protective coating from the end gate. Furthermore, certain ladings, such as sulphur, wet coal, which forms sulphuric 50 acid, and saline water (in refrigerator and

stock cars) cause rolled steel or iron to corrode. On account of its increased strength rolled steel in the form of plates and bars has supplanted wood in car construction but the corrosive action of the elements eats 55 away the rolled steel or iron material reducing their strength and their length of life. This applies to both the load carrying members, such as the sills, plates and diaphragms and also to the lading retaining members, such as side and end walls, floors, hoppers, hopper doors, etc. It has been found that cast metal, particularly cast steel, has more than twice the resistance to corrosion than rolled steel, therefore, one of the objects of 60 the invention is to make the car part of cast metal, preferably cast steel, to enable the car part to resist corrosion, and furthermore, to produce a construction wherein the metal can be disposed and positioned to accommodate 65 the stresses set up by the car in service. Such a cast construction necessitates a minimum amount of material for strength requirements.

Another object is to eliminate the cost and 70 delay in fabricating the numerous component parts of the present structural steel car parts.

Another object of forming the car part of cast metal is to eliminate the possibility of 75 loose connections which would permit relative motion between the component parts of the car part, as it is common knowledge that the vibration of the car in motion, due to rough and uneven track, and steel wheels rolling on steel rails, together with longer trains and high speeds in present day practice, cause riveted joints and built up sections to work loose and the railroads look with favor upon any device which reduces the number 80 of parts and joints as these are the weak parts of the car and the more such weak parts are eliminated, the longer the life of the car.

In the drawings:

Figs. 1 and 2 show a typical application of my device to a railway car.

Figs. 3, 4 and 5 show a typical panel in detail when inside a hopper door.

Figs. 1 and 2 show my cast metal panel adapted for use as a drop door for a hopper 100

type of railway car. In this type of car the hopper doors are arranged in pairs transversely of the car on opposite sides of the center sills 111 and are hinged at their upper margins to the center slope sheet 112 with a connecting member or spreader 113 extending across and joining the lower ends of the hopper doors so that they may be opened or closed in unison upon actuation of the door operating mechanism 114. It will be noted in Fig. 2 that the bulged central portion projects outwardly from the interior of the car so as to increase the cubical capacity of the car.

Figs. 3, 4 and 5 illustrate a modified form of cast metal panel used as a hopper door which comprises a web portion 160 having an integral lateral flange 161 extending continuously around its perimeter, which flange is provided with an integral preferably in-turned re-flange 162 extending continuously around the edges of the panel and connected at the corners of the door by integral gussets. The web portion is formed into a bulge or embossment projecting in the same direction as the flange and occupying the major part of the area of the web and having a circular or elliptical perimeter with portions of the bulge adjacent the side and end portions of the flange preferably leaving a flat marginal portion 163 surrounding the bulge. The depth of the bulge is preferably substantially equal to the depth of the flange. In order to obtain greater strength the central portion of the bulge is formed with relatively thick material which thickness gradually decreases toward the perimeter of the bulge. Lateral ribs 164 may be used to strengthen the bulge portion if necessary to accommodate heavier loads.

When the panel is used as a hinged door the hinge lugs are preferably positioned within the recess formed by the body or web and the flange (and preferably integral with the re-flange) so that the thrust of the load on these members is transmitted to the hinge pins without any cantilever action.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

This is a division of my co-pending application Serial No. 313,906, filed October 20, 1928.

I claim:

1. A cast metal panel forming part of the load retaining means of a railway car comprising a web portion having an integral, continuous lateral flange adjacent its perimeter provided with an integral continuous in-turned re-flange said in-turned re-flange be-

ing wider at the corners of the door than elsewhere.

2. A cast metal panel forming part of the load retaining means of a railway car comprising a web portion having an integral, continuous lateral flange adjacent its perimeter provided with an integral continuous re-flange, said web formed with a bulge projecting outwardly from the interior of the car with portions of its perimeter adjacent the side and end portions of said flange. 70

3. A cast metal panel forming part of the load retaining means of a railway car comprising a web portion having an integral, continuous lateral flange adjacent its perimeter, said web formed into a bulge with portions of its perimeter adjacent the side and end portions of the flange, said bulge projecting in the same direction as the flange. 80

4. A cast metal panel forming part of the load retaining means of a railway car comprising a web portion having an integral, continuous lateral flange adjacent its perimeter, said web formed into a bulge having its depth substantially equal to the depth of the flange with portions of its perimeter adjacent the side and end portions of the flange, said bulge projecting in the same direction as the flange. 85

5. A cast metal panel forming part of the load retaining means of a railway car comprising a web having an integral, continuous lateral flange adjacent its perimeter, said web formed into a bulge of relatively thin portion adjacent the side and end portions of the flange and a relatively thick portion adjacent the central part of the bulge. 95

6. A cast metal panel forming part of the load retaining means of a railway car comprising a web formed into a bulge of relatively thin portion adjacent the side and end portions of the panel and a relatively thick portion adjacent the central part of the bulge. 105

7. A cast metal panel forming part of the load retaining means of railway car comprising a web formed into a bulge of relatively thin portion adjacent the side and end portions of the panel which gradually increase in thickness toward the central part of the bulge. 110

8. A hingeable cast metal door forming part of the load retaining means of a railway car comprising a web formed into a bulge projecting outwardly from the interior of the car so as to increase the cubical capacity of the car. 115

9. A hingeable cast metal door forming part of the load retaining means of a railway car comprising a web formed into a bulge projecting outwardly from the interior of the car so as to increase the cubical capacity of the car leaving flat marginal portions surrounding said bulge. 125

10. A cast metal panel forming part of the 130

- load retaining means of a railway car comprising a web portion having an integral continuous lateral flange adjacent its perimeter, said web formed into a bulge with portions 5 of its perimeter adjacent the side and end portions of the flange, the central portion of said bulge being of relatively thick material which gradually decreases in thickness toward the perimeter of the bulge.
- 10 11. A hingeable cast metal door forming part of the load retaining means of a railway car comprising a web formed into a bulge projecting outwardly from the interior of the car so as to increase the cubical capacity 15 of the car and a continuous integral flange adjacent the perimeter of the door.
12. A hingeable cast metal door forming part of the load retaining means of a railway car comprising a web formed into a bulge projecting outwardly from the interior of the car and a continuous integral flange adjacent the perimeter of the door, said flange formed with a continuous reflare. 20
13. A hingeable cast metal door forming part of the load retaining means of a railway car comprising a web formed into a bulge projecting outwardly from the interior of the car and a continuous integral flange adjacent the perimeter of the door, said flange formed with a continuous reflare connected at the corners 25 of the door by integral gussets.
14. In a railway car, the combination of an opening for the discharge of lading, and a door to close said opening, said door having 30 portions engaging the margins of said opening when the door is in closed position and having the part of the door between said portions bulged outwardly from the interior of the car so as to increase the cubical capacity 35 of the car.
15. In a railway car, the combination of an opening for the discharge of lading, and a door to close said opening, said door having 40 portions engaging the margins of said opening when the door is in closed position and having the part of the door between said portions bulged outwardly from the interior of the car so as to increase the cubical capacity 45 of the car, said door provided with stiffening flanges adjacent its perimeter. 50
